PORTABLE CRIB

Hazard E. Reeves, New York, N. Y.

Application January 24, 1946, Serial No. 643,038

1 Claim. (Cl. 5—97)

1

This invention relates to new and useful improvements in portable cribs.

An object of the invention is to provide a portable crib of neat and attractive appearance, of light weight, and which includes provision for the comfort of the child being carried.

Other objects and advantages of the invention will become apparent from a consideration of the following detailed description taken in connection with the accompanying drawings, wherein a satisfactory embodiment of the invention is shown. However, it is to be understood that the invention is not limited to the details disclosed but includes all such variations and modifications as fall within the spirit of the invention and the scope of the appended claim.

In the drawings:

Fig. 1 is an isometric view showing the crib of the invention with the cover in open position;

Fig. 2 is a top plan view of the crib closed;

Fig. 3 is a front elevational view of the same;

Fig. 4 is a fragmentary enlarged longitudinal sectional view showing the improved crib; and

Fig. 5 is a vertical transverse sectional view through the upper portion of the crib with the cover closed.

Referring in detail to the drawing, the crib of the invention, as shown, comprises a body portion generally designated 10 and a top or cover portion generally designated 11. Body 10 comprises an elongated box-like structure including a front wall 12, a rear wall 13 and a pair of end walls 14. These walls, together with a bottom 15, are of wood, as for example, any suitable plywood, so that the body is strong and yet of light weight. Around the inner edge of the upper portion of the body is a strip 16, also of wood, and attached to the side and end walls by adhesive or the like. This strip extends slightly above the upper edges of the side and end walls of the body, as best shown in Figs. 4 and 5.

Over the outer side of the body is a canvas or other covering 17 and as shown in Figs. 4 and 5, this covering material is carried up over the upper edges of the side and end walls of the body and then up and over the strip 16, as at 18, and has its free end 19 concealed between the inner side of the strip and the inner side of the adjacent wall portion of the body.

The covering material 17 may be attached to the body by adhesive or in any other way generally employed in the manufacture of luggage. On their inner sides, the side and end walls and the bottom wall of the body are all padded, the padding material being indicated at 20, and cov-

2

ering for the padding being a fabric 21 secured in place as by having its end portions disposed between the strip 16 and the adjacent inner portions of the side and end walls.

5 The top or cover 11 is somewhat in the shape of an inverted V in transverse section and is elongated, the same as the body 10. Such top comprises side portions 22 and 23 and end walls 24. These end walls are wedge-shaped or in the form of an inverted V, and each comprises a piece of wood 25 having an opening or cut-out 26 (see Fig. 4) therein, which opening or cut-out is covered as by pieces of wire screening 27 disposed against the inner sides of the wooden pieces 25.

10 In making the cover sides, a single piece of wood is bent into the desired shape and is provided with a pair of spaced longitudinally extending openings 28. When the wood is shaped, it comprises a bowed or curved intermediate or upper portion 29 and lower portions 30, each of the latter comprising an inclining part 31 at the lower edge of the opening 28 and then a vertical part 32.

15 Against the underside of part 29 is a curved spacer member 33 and at each edge of the latter a second spacer member 34 provides means whereby a strip 35 may be secured as by screw 36 to the inner side of the cover but in spaced relation to the edge portions of the cover part 29. Somewhat similarly, a spacer block 37 provides a rigid support for a strip 38 held in place by screw 39. Spacers 34 and 37 hold the strips 35 and 38 in such relation that upper and lower channels 40 and 41 are formed between such strips and the adjacent portions of the cover.

20 These channels slidably receive transparent members 42 and 43. In their inner portions these transparent members overlap, as shown at 44 in Figs. 2 and 3, and each such member is provided with a tab 45 by means of which it may be shifted longitudinally. When either member is shifted into overlapping relation with the other, see Figs. 2 and 3, the openings 28 provide for the entrance of air into the crib and when the transparent members are as shown in Fig. 1, the openings 28 are substantially tightly closed.

25 On the inner side of the cover 11, a strip 46 of fabric covers the inner side of the wooden filler 33 and then has each edge carried over the strips 35, as at 47, and then into the channels 40 whereby the edge of the fabric is concealed. Somewhat similarly, a piece of fabric 48 covers the outer side of the cover and such piece of fabric is shown over the outer sides of parts 29 and then, as at 49, extends down about the bottom parts 30 and under the lower edges of the latter as at 50, and then

to the inner side of the cover and over the strips 38 at 51 and has its edges within the channels 41. In addition, the fabric 49 has pieces cut therefrom and then has the edges of the cuts carried inwardly through the openings 28 and entering into the upper and lower channels 40 and 41 as at 52 and 53.

The screens 27 are secured over the openings 26 by being clamped between portions of the board 25 about such openings and clamping strips 54. The ends of the cover 11 are also finished or covered as by fabric 55 having an opening therethrough corresponding with the opening 26 in the board 25 and having its ends carried in around the opening and clamped against the board by the screen 27. The inside of the cover end walls are also finished with the fabric 56 having its ends about the opening 26 concealed under the clamping strip 54.

The cover 11 is attached to the body 10 as by hinges 59 attaching the rear wall 23 of the cover to the rear wall 13 of the body. On the front wall 12 of the body are elements 60 of latch means, the other elements 61 of which are fixed to the straight or vertical portion 32 of the front wall of the cover. These are actual baggage catches and it will be understood that when the cover is closed, the means comprising the parts 60 and 61 are engaged or latched together so that the cover may not swing open or move relative to the body 10 until such latch means is released. When the latch means is engaged, the entire crib may be lifted and carried from place to place as through the use of the handle 62 extending longitudinally of the crib and disposed centrally thereof for proper balance when carrying the device.

Within the body 10 is shown a child's pillow 63, together with a strap means 64 for securing in place a container 65 which may hold any desired accessories. The corners of the body 10 are shown as reinforced by corner braces 66, preferably of the kind commonly employed in luggage manufacture.

When the cover is closed there is a slight telescoping or overlapping relation between the lower edge portion of the cover and the upper portion of the strip 16. This is as best suggested in Figs. 4 and 5. With this overlapping of the parts, it will be understood that the cover is supported against any tendency toward lateral movement relative to the body, and therefore when the latching structures 60-61 are connected, the body and cover together form a relatively rigid structure which may be conveniently carried by the handle 62. As shown, this handle is secured to the cover structure by means of bolts 62a passing upwardly through the inner strip 33 and the outer curved portion 29 of the cover.

From the above description taken with the drawings, it will be appreciated that the crib of the invention is of neat and attractive appearance and that both the outer and inner surfaces of the wooden structure are fully covered with a

fabric so that there is no danger of either the child or the person handling the crib receiving any splinters or otherwise becoming injured. Additionally, the body portion of the crib is internally padded to provide for the comfort and safety of the child. Adequate ventilation is provided through the screens 27 in the cover structure and it is noted that these screens are located above the position which would normally be occupied by the child in the body 10. By moving any of the transparent slides 42 or 43, additional ventilation is provided for the child or when one of these slides is open, the parent may reach into the crib to draw covers over the child or adjust the position of the child, as any occasion may demand.

Attention is called to the fact that the lower edge portions 32 of the cover are substantially vertical when the cover is in closed position and from continuations of the side and end walls of the body. With this arrangement the conventional latch structure 60-61 may be easily mounted on the respective portions of the crib to properly align when in latching or locking relation.

Having thus set forth the nature of my invention, what I claim is:

A cover for a portable crib and the like comprising a cover somewhat in the form of an inverted V, said cover comprising a piece of material bent intermediate its longitudinal edges to form a pair of said walls for said cover, said material having its lower longitudinal edge portions bent to extend in parallel relation, said side walls having longitudinally extending openings in their intermediate portions, spacers at the inner sides of said member inwardly of the edges of said openings, strips secured to said spacers and extending toward the edges of the openings and substantially parallel with the portions of the member about the edges of the opening and with such edge portions and the spacers forming channels at the upper and lower edges of said openings, and a plurality of transparent members in each of said channels and slideable therein between extended positions closing said openings and overlapping positions exposing said openings.

HAZARD E. REEVES.
